Term of patent 14 years

Int. Cl. D23—04

U.S. Cl. D23—149

FIG. 2

FIG. 1

FIG. 3

FIG. 1 is a side elevational view of a foreline molecular trap for a vacuum system embodying my new design;

FIG. 2 is a top plan view thereof; and

FIG. 3 is a right end elevational view thereof.

The electrical cable has been shown as broken away in the three views to indicate indeterminate length.

I claim:

The ornamental design for a foreline molecular trap for a vacuum system, as shown and described.
